PAPER BOX OR CARTON

Samuel Katz, New York, N. Y., assignor to Gibraltar Corrugated Paper Co., Inc., North Bergen, N. J., a corporation of New Jersey

Application November 22, 1933, Serial No. 699,272

2 Claims. (Cl. 229—34)

This invention relates to improvements in paper boxes or cartons, and has more particular relation to boxes or cartons of the so-called "knock-down" type usually constructed of paper-board, either plain or corrugated.

The principal object of the invention is to form the body of the box or carton of cardboard so scored and constructed that when assembled, the parts will be automatically locked in position against accidental displacement, but at the same time, be capable of being "knocked-down" for shipping.

A further object of the invention is to provide a box or carton of corrugated paper capable of being "knocked-down" for shipping and having its parts locked in position when assembled.

Another object of the invention is to provide a box struck from a single blank of corrugated paper in which the box may be held in its assembled condition by end flaps which automatically lock with slits formed in a portion of the corrugated paper.

The invention also has other objects, all of which will be hereafter more particularly set forth and claimed.

In the drawing forming part of the specification,

Figure 1 represents a perspective view of a box embodying my invention, the same being partly broken away to expose the interior and the cover and ends being shown in dotted lines.

Figure 2 represents a detail vertical section of the same on the line 2—2 of Figure 1.

Figure 3 represents an end elevation broken away and showing the locking construction of the end flaps, and

Figure 4 represents a top plan view of one end of the box blank, the opposite end being broken away.

Described in general terms, the box, which is formed from a single blank of corrugated paper, comprises a bottom 11, sides 16, end flaps 17, ends 12, locking flaps 13 and a cover 25. The cover 25 may be of any ordinary construction arranged to fit over the box proper, and forms no part of the present invention.

The paper from which the box is constructed comprises an inner layer of paper 26, an outer layer 27 and an intermediate corrugated or "waved" strip 20, as best shown in Figure 3.

The corrugations 20 extend longitudinally of the bottom 11 for a purpose to be hereinafter described and as the ends 12 and the locking flaps 13 form an integral part of the bottom, the cor-

rugations extend vertically in these parts when the box is formed.

Each of the locking flaps 13 is formed on its outer edge with two locking lugs 14. The flap 13 is slightly less in width than the end 12 so that this flap may double down inside of the sides 16 when the box is assembled and as shown in Figure 1.

At the points marked 2 and 3 the blank is scored between each end 12 and its companion locking flap 13; the distance between the scores 2 and 3 equalling the thickness of the end flaps 17 which extend between their respective ends 12 and the locking flaps 13 that double down inside of them when the sides of the box have been raised to positions at right angles to the bottom 11. The end flaps 17 are connected to the sides 16 and are scored as at 4 and 5 so that these end flaps may be doubled inward along the scored lines. The flaps 17 are slightly less in height than the sides 16 to allow a clear space 19 for accommodating the bend of the end flaps 12 and 13 when the box is assembled.

Scored lines 1 are formed between each end of the bottom and its end flap 12. The paper layer 26 of the bottom is slit as at 15 at each end. This slit only extends through the paper 26 and a portion of the corrugated paper 20 so that when the locking flap 13 is doubled over the flap 17 and forced into a vertical position as shown in Figure 1, the locking projections 14 will depress the paper 26 against the yielding pressure of the corrugations 20 until these lugs pass the slits 15, when the paper 26 will be again forced upward by the spring of the corrugations 20 and lock the lugs firmly in position as shown in Figure 2. When locked in this position the lower end of the flap 13 and the lugs 14 are held firmly in position as the forcing down of the paper 26 is against the

spring tension of the corrugations and these corrugations by their tendency to resume their normal positions exert considerable friction on the lower end of the locking lugs 14 and as these lugs cannot move upward and have a tendency to spring forward, the lugs 13 are locked firmly against any accidental displacement.

This locking effect is accomplished by pushing the flap along the upper surface of the paper 26 by employing force and until the lugs 14 snap into position as above described.

After being so locked in position the flaps 13 cannot again be drawn forward into the box except by employing some tool to depress the bottom and disengage the walls of the slots 15 from

the lugs 14. This locking feature thus becomes a positive lock having spring characteristics.

It will be seen from the above that the body of this box or carton is struck from a single piece of material and has great rigidity because of the corrugated construction and that the blanks may be shipped in a flat condition in very small packages and may be instantly erected into rigid boxes locked in the most positive manner in their assembled condition. Ordinary strains and packing of such boxes or cartons will have no effect on the structure of the boxes such as might disengage the locking flaps 13, as these flaps, together with the flaps 17 and the end 12, form a rigid unyielding structure in which the lugs 14 cannot be forced out of engagement with the walls of the slits 15 except by deliberate intent.

What I claim is:

1. In a collapsible box, the combination with a single paper blank having a bottom section com-

prising a slit flat bottom layer and compressible corrugations connected below the same, side sections having flaps at each end, end sections, locking flaps connected to the end sections and having locking projections that engage the slits in the bottom and partly compress the corrugations which re-act to hold the locking flaps firmly in locking position.

2. In a collapsible box, the combination with a single paper blank having a bottom section composed of flat top and bottom layers spaced and separated by wave-like corrugations, the top layer only having locking slits therein, side sections having flaps at each end, end sections and locking flaps having locking tongues which engage the walls of the slits in the bottom and partly compress the corrugations which re-act to hold the tongues firmly in locking positions.

SAMUEL KATZ.
